SMASHBOARD SIGNAL

Herbert L. Bone, Pittsburgh, Pa., assignor to The
Union Switch & Signal Company, Swissvale,
Pa., a corporation of Pennsylvania

Application May 10, 1935, Serial No. 20,739

4 Claims. (Cl. 246—486)

My invention relates to smashboard signals, that is, to signals which are so designed that the signal arm, commonly called a smashboard, will be struck by a train and broken if the train passes the signal when the smashboard occupies its stop position.

One object of my invention is to provide a smashboard signal of the type described that is suitable for use on multiple track electrified roads at locations where clearance conditions make it necessary to obtain the stop and clear positions by moving the smashboard vertically through a relatively large distance.

Another object of my invention is to provide a signal of the type described which can be constructed at a minimum cost, and which will require a minimum amount of maintenance and upkeep.

I will describe one form of smashboard signal embodying my invention, and will then point out the novel features thereof in claims.

In the accompanying drawings, Fig. 1 is an elevational view of a signal embodying my invention mounted on a signal bridge in the preferred manner. Fig. 2 is a left-hand side view of the apparatus shown in Fig. 1.

Similar reference characters refer to similar parts in both views.

Referring to the drawings, a signal embodying my invention is adapted to be mounted above the track over which it governs traffic, and as here shown it is mounted in a framework A secured to a signal bridge B directly above a track C. The signal bridge B may be of any preferred construction, but as here shown it is of the usual type employed on multiple track electric roads for the purpose of supporting the usual signals, overhead trolley lines, feeder wires, and the like. The framework A is intended to serve not only as a support for the signal, but also as a convenient means for securing access to the signal to facilitate inspection and maintenance, and it may comprise any construction which is suitable for its intended purpose. In the form illustrated, it comprises angle bars 1 secured together, as by welding, to form a rectangular box-like construction, the upper part of which supports an upper platform 2, and the lower part of which supports a lower platform 3. The upper platform 2 is substantially on a level with the top of the signal bridge, and the construction of the framework is such that it forms a railing around the three sides of the platform 2 which are disposed away from the signal bridge. To permit ready

access to the lower platform 3, a ladder 4 is provided between the upper and lower platforms.

The signal proper comprises a smashboard 5 secured to the lower end of a vertical rod 6 which is pivotally attached, at vertically spaced points, to upper and lower arms 7 and 8 by means of horizontal pivot pins 7^a and 8^a mounted in the outer ends of these arms. For reasons which will become apparent as the description proceeds, it is desirable that the arms 7 and 8 should be rigid and yet light in weight, and to this end these arms are preferably constructed of structural members in the manner shown, although this particular construction is not essential to my invention. The upper arm 7 is secured at its lower end to a horizontal shaft 9 which is journaled in bearings 10 secured to certain ones of the angle bars 1 forming part of the framework A, while the lower arm 8 is similarly secured to a horizontal shaft 12 which is journaled in bearings 13 secured to certain other angle bars 1 also forming part of the framework A. The lower arm 8 is similar in all respects to the upper arm 7 with the exception that the side pieces 8^b of the lower arm extend past the shaft 12 and are provided with counterweights 15. The parts are so proportioned that the upper and lower arms 7 and 8 are free to rotate through an angle of substantially 90° between an upper position in which they are disposed at an angle of substantially 45° above the horizontal and a lower position in which they are disposed at an angle of substantially 45° below the horizontal, and that during rotation of the arms from one position to the other they will remain substantially parallel. The parts are further so proportioned that when the arms occupy their upper positions, the smashboard 5 will be raised to what I shall term its "clear" position, in which position it will be out of the path of a train passing the signal on the track C; but that, when the arms 7 and 8 are rotated to their lower positions, the smashboard 5 will then be lowered to what I shall term its "stop" position, in which latter position a locomotive passing the signal will strike the smashboard and break it, thus warning the engineman that traffic conditions in advance are dangerous. The weights of the counterweights 15 are such that these counterweights will approximately balance the weights of the two arms 7 and 8, the vertical rod 6 and the smashboard 5.

The arms 7 and 8 may be moved to their upper and lower positions to move the smashboard 5 to its clear and stop positions by any suitable form of operating mechanism. As here shown, these

arms are operated by a standard switch movement M through the medium of an operating rod 16, the upper end of which is connected with the actuating member 17 of the mechanism M, and 5 the lower end of which is connected with a crank 18 secured to the shaft 12. The switch movement M may comprise any of the well-known switch movements of either the electric or pneumatic types, so long as it is provided with a circuit controller which will indicate when the mechanism occupies its two extreme positions, the particular mechanism here illustrated being of the pneumatic type shown and described in an application for Letters Patent of the United States, Serial No. 15 665,914, filed by me on April 13, 1933, for Railway switch operating apparatus. The lock rods and point detector rods, as well as certain other parts shown in the patent just referred to are, of course, not required when the switch movement is used in 20 my present invention and these parts are therefore omitted from the drawings.

As shown in the drawings, the smashboard 5 occupies its upper or clear position. When it is desired to move the smashboard to its lower or stop 25 position, the switch movement M is energized through suitable control mechanism of well-known construction forming no part of my present invention and therefore not shown in the drawings. This causes the operating rod 16 to 30 move downwardly which movement, in turn, causes the smashboard 5 to move from its clear to its stop position. When the smashboard has reached its stop position, indication circuits not shown are completed through the circuit controller of the switch movement to indicate that the smashboard is then in its stop position where it 35 will be struck by a train should the train pass it. It should be noted that the smashboard is not moved to its stop position by gravity, and that it 40 is prevented from moving in both its stop and clear positions by the cam arrangement of the switch and lock movement.

When it is desired to move the smashboard to its clear position, the switch movement is energized through the control circuits, and the action 45 under these conditions is the reverse of that just described. An indication circuit is completed through the switch movement circuit controller when the smashboard has reached its clear position.

One advantage of a smashboard signal embodying my invention is that it provides a convenient means for obtaining the large amount of vertical movement which is necessary to operate the 55 smashboard under the conditions where this type of signal is required.

Although I have herein shown and described only one form of smashboard signal embodying my invention, it is understood that various 60 changes and modifications may be made therein within the scope of the appended claims without

departing from the spirit and scope of my invention.

Having thus described my invention, what I claim is:

1. A railway signal comprising two arms pivotally supported above a railway track for rotation about vertically spaced horizontal axes, a vertical rod pivotally attached to the free ends of said arms in such manner that said arms will remain substantially parallel when they are rotated about 5 their pivotal supports, means for rotating said arms, and a smashboard secured to said rod. 10

2. A railway signal comprising a supporting framework disposed above a railway track, two arms pivotally supported at one end in said framework at vertically spaced points for rotation about horizontal axes, a vertical rod pivotally attached to the free ends of said arms in such manner that said arms will remain substantially parallel when said arms are rotated about 20 their pivotal supports, a smashboard secured to the lower end of said rod, and means for rotating said arms to raise and lower said smashboard between an upper position in which said smashboard is out of the path of a train traversing said 25 track and a lower position in which said smashboard projects into the path of a train traversing said track.

3. In combination, a signal bridge spanning a railway track, a framework secured to said bridge, 30 two arms pivotally supported in said framework at vertically spaced points for rotation about horizontal axes, a vertical rod pivotally attached to the free ends of said arms in such manner that said arms will remain substantially parallel and 35 said rod will remain substantially vertical when said arms are rotated about their pivotal supports, a smashboard secured to the lower end of said rod, and means including a switch movement for rotating said arms to move said smashboard to an upper or clear position and a lower or stop 40 position.

4. In combination, a signal bridge spanning a railway track, a framework secured to said bridge, two vertically spaced horizontal shafts rotatably mounted in said framework, two arms secured to said two shafts respectively to rotate therewith and each provided at their free ends with a pivot pin, a vertical rod pivotally attached to said two arms by means of said pivot pins in such manner that when said arms are rotated they 50 will remain substantially parallel, a smashboard secured to the lower end of said rod, counterweights secured to one of said arms to counterbalance the weights of both said arms, said rod and said smashboard, a crank secured to one of 55 said shafts, an operating rod connected with the free end of said crank, and power means for actuating said operating rod.
